UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed August 25, 1923, Serial No. 659,273. Renewed October 10, 1924.

This invention relates to manifolding typewriting machines of the continuous billing type, in which a composite sheet or web is fed around the cylindrical platen, 5 the web comprising several plies of work-sheets having successive corresponding forms printed thereon, said plies being sometimes separated from each other and sometimes joined at their side edges to form a fan-folded web, the various plies having carbon-sheets interleaved therebetween which are displaceable at intervals along the web to fresh sets of forms. The invention relates more particularly to means to facilitate the 10 relative displacing or shifting between the carbon-sheets and the work-sheets.

One form of this kind of machine is disclosed in the patent to Wernery & Smith, No. 1,132,955, dated March 16, 1915. In 20 said machine the platen is mounted in a swing frame by which it may be displaced upwardly, from its normal typing position, so as to enable that portion of the web containing the carbon-sheets to be straightened 25 out preparatory to a carbon-displacing operation.

Another form of machine for handling this kind of work is disclosed in the application of B. C. Stickney, Serial No. 647,501, 30 filed June 25, 1923 (now Patent No. 1,582,438, of April 27, 1926), in which there is provided means to so condition the web that there may be a relative shifting between the work-sheets and the carbon-sheets. 35 without lifting the platen, the platen remaining always in its usual typing position. To this end there is provided in said machine a normally-ineffective curved table, which may be moved to effective position to 40 so condition the web that it is disposed in a curve of comparatively large radius, after which a pivoted carbon-carrier, to which the ends of the carbon-sheets are attached, may be actuated to draw the carbon-sheets 45 rearwardly to displace them relatively to the work-sheets while the latter are being held, the leading edges of the work-sheets remaining around the platen, so that they may be readily fed with the carbon-sheets around 50 the platen after a carbon-displacing operation.

Still another form of machine of this general class is disclosed in my co-pending application Serial No. 645,995, filed June 18, 55 1923 (now Patent No. 1,578,941, of March

30, 1926), in which there is provided a curved table which is relatively fixed, over which the web is conducted to the platen, a carbon-carrier being arranged behind said table and slideable on a rearward extension 60 of said table, so that it may travel with the web towards the platen and may be pushed rearwardly on said table to withdraw the web around the platen to condition the web for a relative shifting between the carbon-sheets and the work-sheets by freeing the carbon-sheets from said platen. After the carbon-sheets have been freed from the platen they are held while the work-sheets are fed forward relatively thereto by the 70 platen to strip the carbon-sheets from the typed set of forms and bring a fresh set of forms into typing relation with respect to the carbon-sheets.

A feature of the present invention is the 75 provision of a relatively fixed curved table disposed at the back of the platen and a pivoted carbon-carrier mounted independently of said table, which may be swung rearwardly to withdraw the carbon-sheets 80 with the work-sheets around the platen to free the carbon-sheets from said platen, after which the work-sheets may be fed forwardly, while the carbon-sheets are held, to shift said work-sheets relatively to the 85 carbon-sheets; a gage being provided at the delivery side of the platen to determine the extent of shifting of said work-sheets.

Another feature of the invention is the provision of means whereby slack is created 90 in that portion of the web between the platen and the carbon-carrier, to avoid hindrance of the feeding of the web around the platen, which sometimes results in slipping between the platen and the work-sheets during rapid line-spacing operations. This slack is created in the web by the carbon-carrier when it returns to its normal position.

A feature of the invention is the provision 100 of means comprising a guide-plate to prevent the slack, created in the web, from piling up on the platen.

A further feature of the invention resides in the provision of stopping means to limit 105 the reciprocatory movements of the carbon-carrier, said means comprising an actuating arm provided with a pin, which plays back and forth in a slot of an arm connected with the carbon-carrier, said pin engaging in the 110

end of the slot in both the normal position and the operated position of the carbon-carrier to arrest said carbon-carrier in said positions.

5 Other features and advantages will hereinafter appear.

In the accompanying drawings,

10 Figure 1 is a part-sectional side view of an Underwood typewriting machine, showing the invention applied thereto, and showing the parts in their normal typing position, and a set of forms nearing the completion of typing.

15 Figure 2 is a view similar to Figure 1, but shows the carbon-carrier swung to its effective position to withdraw the web around the platen to free the carbon-sheets from said platen after the feed-rollers have been released.

20 Figure 3 is a top plan view of the machine, with the parts shown in the position indicated in Figure 2.

25 Figure 4 is a view similar to Figure 2, some of the parts being omitted, and shows the feed-rollers thrown on and the work-sheets advanced around the platen to a gage while the carbon-sheets are held free from the platen by the carbon-carrier.

30 Figure 5 is a diagrammatic side view, showing the carbon-carrier raised to its normal position to thus create slack in the web behind the platen, and showing also the web fed to the second gage to bring the bottoms of the typed set of forms to the knife, where 35 they may be severed, and the leading ends of the carbon-sheets to the printing point, to proceed with the typing of a fresh set of forms.

35 Type-bars 10 strike against the front of 40 a revoluble platen 11, which is journaled in the usual manner in a platen-frame comprising ends 12 and a rear paper-shelf 13. The usual front and rear feed-rolls 14 run on the under side of the platen. They may 45 be released, or thrown from the platen, by means of a finger-piece 15, connected by a link 16 to an arm 17, fast on a shaft 18. The shaft 18 is provided with flats, against which arms 19, forming part of levers 20, 50 are held by spring-pressure. The levers 20 are pivoted on a shaft 21, so that when the finger-piece 15 is actuated, and the arms 19 spread apart by turning of the shaft 18, the levers 20, which support the pressure- 55 rolls, are rocked on the shaft 21 to release the rolls. This roll-releasing structure is that commonly found in the standard Underwood typewriting machine.

60 The work-web, usually comprising superposed plies 22 (which may be separate or which may form a fan-fold), is drawn up from a supply-spool, or from a zigzag folded pile (not shown), but which may be contained in a receptacle arranged in the 65 rear of the typewriting machine and its

stand. In the normal or typing position of the parts, the work-webs on rising from their supply are turned around and pass for a distance along the rear portion 24 of a table 25, by means of which they are turned or 70 directed toward a rod 26 supported at its ends on a pair of arms 27, which, for purposes hereinafter mentioned, are obviously supported at 28. The work-plies are turned around the rod 26, and are thus directed 75 downward through a carbon-carrier 29 where they are interleaved with carbons 30. Each of the carbons 30 has its rear end attached to one of two blades 31, carried by standards 32 on the ends of a plate 33. The 80 plate 33 is secured to a bar 34, supported at its ends by ears 35, offset one from each of the pivotally-mounted arms 27.

85 From the carbon-carrier the composite web drops in the form of a slack 36 (that is to say when the parts are in the Figure 1 or typing position) again onto the surface of the table 25, and is thus led forward on the surface of the table 25 over the front edge 37 thereof, slightly above and forward of the rear upper edge of the paper-shelf 13. It will be noted that the table 25 is of long arcuate curvature, rising at its center portion well above the upper edge of the paper-shelf and turning down at its forward end so 90 as to direct the web tangentially therefrom, over the paper-shelf 13 to the rear under face of the platen. The web is thus guided around the platen, up across the printing line, and along and in front of a staff 38, to 95 which is adjustably secured, by means of a thumb-screw 39, a gage 40, the purpose of which gage will hereinafter more fully appear.

100 The table 25 is a stationary table. It is supported at either side, at the front part thereof, by a pair of arms 41 turned upward from brackets 42, which latter are extended horizontally forward from the arms 41, and at their forward ends are secured to the 105 under face of the usual cross tie or bar 43 which connects the side pieces of a carriage 44. In its rear part, the table 25 is supported by a pair of arms 45, which are connected to and supported by downwardly-inclined extensions 46 of the brackets 42. At the ends of the inclines 46 of the brackets 42, these brackets are again offset horizontally at 47, rearward, and at their rear ends are again offset downward at 48. The downward offset or rear 48 of each of the brackets 42 is secured to a bar 49, which extends crosswise of the machine and serves to connect these brackets and to form with the brackets a frame. Depending from the bar 110

49 are a pair of brackets 50, on which are journaled rollers 51 which ride on a rail 52. The rail 52 is supported by a pair of brackets 53, one at each side of the machine, and each of the brackets 53 being secured, as at 115 120 125 130

54, to the main frame 55 of the machine. The platen-carriage 44 is mounted on a rail 56 for movement in letter feed and return directions on the main frame 55 of the machine. It, therefore, follows that the frame, which is formed by the brackets 42 and the rear cross-bar 49, is in the nature of a sub-carriage attached to the platen-carriage and supported on front and rear rails 56 and 52, respectively, for movement in letter feed and return directions with the platen-carriage; and that the table 25, over which the web is fed to the platen-carriage, is a table which travels with the latter, by virtue of its connections and supports 41 and 45 on the bracket-arms 42 and 46, respectively.

In order that the slack 36 in the web between the carbon-carrier and the platen may not collapse or slide forward off the table 25 and down onto the platen, a guard, in the form of a curved plate 57, is provided. This plate 57 has ears 58 turned from the edges thereof, and these are offset under the side edges of the table 25 where they are secured at 59 to the table; the guard 57 being thus supported and carried by the table 25 in the movements of the latter. The guard 57 is curved tangentially to the table at the front of the latter; a space being provided between the guard and the table at 60 just sufficient to permit passage of the web between the work. The guard-plate may press lightly against the web to retain the latter; that is to say, prevent the web from slipping forward between the work. Guards 61 on the paper-shelf 13 are also provided for the side edges of the table. These guards are in the form of ears struck up from flat plates 62 which have their upper ends curled at 63 to be sprung over and retained by the curved edge 64 of the paper-shelf 13. The guards 61 are thus adjustable over the paper-shelf 13 to accommodate different widths of web.

Assuming that typing on the leading form-section of the web has been completed, the first step in conditioning the web, preliminary to a relative shift of the carbons and work-plies, to withdraw the carbons from the typed leading form-section to set the same in the next untyped form-section, is to eliminate any slack 36 remaining in the web and to flatten the web out on the curved surface of the table 25, so that the relative movement of the carbons and work-plies may be a smooth and easy movement made without possibility of fouling of the sheets. The movement of the carbon-carrier from Figure 1 to Figure 2 position is, however, a further important object, to wit, the retraction of the web around the platen so as to clear the carbon-sheets from the platen.

In the use of the apparatus shown in the drawings, actual shift of the work-plies relative to the carbons is effected by for-

ward feed of the work-plies around the platen after the parts have been moved to the Figure 2 position. If this operation is to take place, it is obvious that the carbons must be clear of the platen, so that they will not move forward, so that they may be held against forward movement when the platen acts to feed the work-plies forward. As a preliminary to the movement of the carbon-carrier to the Figure 2 position, the feed-rolls 14 are released, so that the retraction of the web by the carbon-carrier may be effected, so that there may be no drag on the web and consequently on the carbon-carrier which would otherwise result from pressure of the feed-rolls on the web.

In moving the carbon-carrier from Figure 1 to Figure 2 position, the left-hand carbon-carrier arm 27 has a slotted arm 65 which forms a bell-crank therewith. The carbon-carrier arms 27, as hereinbefore stated, are pivoted at 28. The pivot is provided by a rock-shaft 66, which has its bearings in ears 67 turned down from the lower horizontal portions 47 of the brackets 42, one at each side of the carriage. Working in a slot 68 of the arm 65 is a pin 69 on the end of one arm 70 of a bell-crank journaled at 71 on an ear 72 turned forward from the downwardly-inclined portion 46 of the left-hand bracket 42. The other arm 73 of this bell-crank is connected at 74 to a link 75, the other end of which link connects at 76 to a rear arm 77 of another bell-crank journaled at 78 on the left-hand bracket-arm 41. The other arm of this latter bell-crank is a forwardly-extending arm 79, which terminates in a handle 80, by means of which the carbon-carrier is operated. It follows that when the handle 80 is drawn forward and downward from Figure 1 to Figure 2 position, the link 75 is lifted, the arm 70 rocked upward and rearward to cause the pin 69 to rock the carbon-carrier-supporting arms 27 downward and rearward. The pin-and-slot connection 68-69 between the arms 65 and 70 provides the necessary play between the levers thus connected. The end wall of the slot 68, as shown in Figures 1 and 2, by engagement of the pin 69 therewith, determines the Figure 1 and Figure 2 positions of the carbon-carrier, and consequently determines the throw of the carbon-carrier and of the operating lever 79.

The parts being in Figure 2 position, the pressure-rolls 14 are then re-applied preliminary to feed of the work plies forward. This feed may be effected by turning the platen by means of one of the finger-knobs 81 or by the line-space wheel 82, ordinarily found upon and made fast to the axle of the platen. During this forward rotation of the platen, the handle 80 may be held by the operator to hold the carbon-carrier in Figure 2 position against movement with

the work-plies. The lower end 83 (see Figure 4) of the arm 84, unitary with the gage 40, serves to determine, by registration therewith of the leading ends of the work-plies, 5 the amount of advance of the work-plies required properly to position the carbons with the next untyped form-sections of the work-plies, and to clear the carbons of the leading typed form-sections after detachment of 10 the latter.

It remains then to advance the composite web to position wherein such detachment of the leading type form-sections may be effected, and to position the web at commencement 15 of typing at the next untyped form-sections thereof. It is for this purpose that the gage 40 is provided, as shown in Figure 5. The movement of the composite web to bring the leading ends of the work-plies 20 to the gage 40 is effected by a further forward rotary movement of the platen. Preliminary to such further forward rotary movement of the platen, and in order that the carbons may be advanced with the work-plies during such movement, the handle 80 is thrown back to Figure 1 position to return 25 the carbon-carrier to normal position, as indicated in Figure 5, thereby re-establishing a slack 36 in the work-plies and carbons. 30 Such re-established slack will be not only sufficient to permit advance of the web, from Figure 4 to Figure 5 position, but will also be sufficient to take care of the subsequent line-space feed of the web in the typing of 35 the next form.

When the leading edges of the typed form register with the gage 40, the rear edges of the leading typed form register with the cutting edge of a blade 85, so that the typed 40 form-section may be severed from the rest of the web by drawing the web against the blade. The blade 85, as shown in Figure 3, is secured at its ends to brackets 86, in turn, secured to the end pieces 12 of the platen-frame. The brackets 86 also serve to support a cross or table plate 87, to which the gage-staff 38 is centrally secured at 88. After detachment of the typed form-section, or without detaching such form-section, 45 typing on the next form may be commenced.

Variations may be resorted to within the scope of the invention, and portions of the improvements may be used without others.

Having thus described my invention, I claim:

1. In a continuous billing typewriting machine, the combination of a carriage, a revoluble platen on said carriage around 60 which a work-web comprising continuous work-sheets may be fed with interleaved carbon-sheets, a pivoted carbon-carrier to travel with said carriage to retract the work-sheets with the carbon-sheets around 65 the platen to free the carbon-sheets from

the platen, a curved table over which the web is stretched when retracted, said table pocketed at its forward end to receive a loop of work-web, feed-rolls to advance the web while the carbon-sheets are held, a gage 70 to determine the extent of advancement of said work sheets, said carbon-carrier movable forwardly from sheet-retracted position to gather the web into a loop upon said table, and means to detain said carbon-carrier in its forward position during the taking up of the loop by the platen. 75

2. In a continuous billing typewriting machine, the combination of a carriage, a revoluble platen on said carriage around 80 which a work-web comprising continuous work-sheets may be fed with interleaved carbon-sheets, a pivoted carbon-carrier to travel with said carriage to retract the work-sheets with the carbon-sheets around 85 the platen to free the carbon-sheets from the platen, a curved table over which the web is stretched when retracted, said table pocketed at its forward end to receive a loop of work-web, feed-rolls to advance the web, 90 means to lock said carbon-carrier in its actuated position to hold the carbon-sheets while the work-sheets are being advanced, a gage to determine the extent of advancement of said work-sheets, means to restore 95 said carbon-carrier to normal position, so that the carbon-sheets may be fed with the work-sheets, said carbon-carrier effective in its return to normal position to gather the web into a loop upon said table, a second 100 gage to determine the extent of advancement of the carbon-sheets with the work-sheets, a knife to sever the typed portions of the work-sheets and means to detain said carbon-carrier in its forward position during 105 the taking up of the loop by the platen.

3. In a continuous billing typewriting machine, the combination of a carriage, a revoluble platen on said carriage around 110 which a work-web comprising continuous work-sheets may be fed with interleaved carbon-sheets, a sub-carriage connected to travel with said carriage, a carbon-carrier pivoted on said sub-carriage, a finger-piece to operate said carbon-carrier to retract the 115 work-sheets with the carbon-sheets around the platen to free the carbon-sheets from said platen, a curved table over which the web may be stretched to condition it for a carbon-shifting operation, said sub-carriage comprising upwardly-extending arms to support the forward end of said curved table, and rearwardly and upwardly extending arms to support the rear end of the curved table, said finger-piece being pivoted 120 on one of the table-supporting arms.

4. In a continuous billing typewriting machine, the combination of a carriage, a revoluble platen on said carriage around 125 which a work-web comprising continuous work- 130

sheets may be fed with interleaved carbon-sheets, a carbon-carrier comprising two arms, said carbon-carrier occupying normally a vertical position, a sub-carriage, 5 said carbon-carrier being pivotally mounted at the lower end of its arms on said sub-carriage, a finger-piece to swing said carbon-carrier rearwardly and downwardly to a horizontal position to retract the work-sheets and the carbon-sheets about the platen to free the carbon-sheets from said platen, a curved table over which the web may be stretched, so as to extend tangentially from said table to the carbon-carrier 10 and tangentially from said table to the platen to facilitate the shifting of the work-sheets, and feed-rolls co-operating with the platen to feed the work-sheets.

5. In a continuous billing typewriting machine, the combination of a carriage, a revolute platen on said carriage around which a work-web comprising continuous work-sheets may be fed with interleaved carbon-sheets, a pivoted carbon-carrier to 20 travel with said carriage to retract the work-sheets with the carbon-sheets around the platen to free the carbon-sheets from the platen, a relatively fixed curved table to travel with said carriage over which the work-web may be stretched preparatory to 25 a relative shifting between the work-sheets and the carbon-sheets, said carbon-carrier being effective when swung from its operative position to its normal position to produce a slack-containing loop in the web on 30 said table at the introductory side of the platen to facilitate line-spacing of said web about said platen, and loop-pocketing means between the table and the platen to prevent 35 slack from said loop from piling up on said platen, while allowing the web to feed to the platen.

6. In a continuous billing typewriting machine, the combination of a carriage, a revolute platen on said carriage around which a work-web comprising continuous work-sheets may be fed with interleaved carbon-sheets, a pivoted carbon-carrier to 45 travel with said carriage to retract the work-sheets with the carbon-sheets around the platen to free the carbon-sheets from the platen, a relatively fixed curved table to travel with said carriage over which the work-web may be stretched preparatory to 50 a relative shifting between the work-sheets and the carbon-sheets, said carbon-carrier being effective when swung from its operative position to its normal position to produce slack in the web at the introductory 55 side of the platen to facilitate line-spacing of said web about said platen, and a guard-plate secured to the curved table at its forward end to prevent the slack from piling up on said platen.

7. In a continuous billing typewriting

machine, the combination of a carriage, a revolute platen on said carriage around which a work-web comprising continuous work-sheets may be fed with interleaved carbon-sheets, a pivoted carbon-carrier to 70 travel with said carriage to retract the work-sheets with the carbon-sheets around the platen to free the carbon-sheets from the platen while the web remains in position around the platen, a fixed curved stripping 75 table under the carbon-carrier, said carbon-carrier comprising two arms, an extension on one of said arms, said extension having a closed end slot therein, and instrumentalities supported on said carriage, including a 80 bell-crank engaging said extension to actuate said carbon-carrier, said bell-crank being so arranged to co-operate with said slot so as to lock the carbon-carrier unyieldingly in its extreme positions.

8. In a continuous billing typewriting machine, the combination of a carriage, a revolute platen on said carriage around which a work-web comprising continuous work-sheets may be fed with interleaved 90 carbon-sheets, a pivoted carbon-carrier to travel with said carriage to retract the work-sheets with the carbon-sheets around the platen to free the carbon-sheets from the platen, said carbon-carrier comprising two 95 arms, an extension on one of said arms, said extension having a closed end slot therein, means comprising a bell-crank to actuate said carbon-carrier, and a pin on said bell-crank engaging in the slot of said extension 100 to form a connection between said bell-crank and said carbon-carrier, said pin engaging the ends of said slot to limit the motion of said carbon-carrier in both directions.

9. In a continuous billing typewriting machine, the combination of a carriage, a revolute platen on said carriage around which a composite web comprising plies of work-sheets and interleaved carbon-sheets may be fed, an extension at the rear of said carriage, a carbon-carrier supported on said extension, a curved carbon-stripping table fixed on said extension, and over which the web may be stretched, to condition it for a carbon-shifting operation, the top of said 110 table being below the normal forward position of said carbon-carrier, and a finger-piece on said extension to operate said carbon-carrier to retract the composite web around the platen to free the carbon-sheets from said platen; said carbon-carrier in its forward movement to normal position forming a slack in the web.

10. In a continuous billing typewriting machine, the combination of a carriage, a 115 revolute platen on said carriage around which a composite web comprising plies of work-sheets and interleaved carbon-sheets may be fed, a curved carbon-stripping table fixedly connected to the rear of said car- 120

130

riage, said table extending rearwardly and downwardly from said carriage, a normally upstanding carbon-carrier mounted on said carriage independently of said table to be actuated backwardly over said table and downwardly, to retract the composite web around the platen to free the carbon-sheets from said platen, and condition it for a carbon-shifting operation, a portion of said web being disposed in the rear of said table tangent thereto, said carbon-carrier capable of looping the web on said table adjacent the forward end of the latter upon its forward stroke to normal position, and a finger-piece on said carriage to actuate said carbon-carrier.

11. In a continuous billing typewriting machine, the combination of a carriage, a revolute platen on said carriage around which a work-web may be fed, a curved carbon-stripping paper-table at the rear of the platen, the forward end of said table sloping downwardly to the platen, means to produce slack in the web on the table in the rear of the platen, and a paper-guard

mounted in position on said table to prevent the slack from piling up directly behind the platen.

12. In a continuous billing typewriting machine, the combination of a carriage, a platen around which a continuous composite web comprising work-sheets and interleaved carbon-sheets may be fed, a carbon-carrier pivoted on the carriage to withdraw the composite web about the platen to free the carbon-sheets from said platen, so that the work-sheets may be advanced relatively to the carbon-sheets, a finger-piece pivoted on said carriage, and connecting means between said finger-piece and said carbon-carrier, said connecting means being effective to lock the carbon-carrier unyieldingly in its normal position, to prevent accidental operation of said carbon-carrier, said connecting means being also effective to lock the carbon-carrier unyieldingly in its operated position to hold the carbon-sheets while the work-sheets are being shifted relatively thereto.

JOHN WALDHEIM.
